Primary Examiner — Darlington Ly(74) *Attorney, Agent, or Firm* — Morgan, Lewis & Bockius LLP(57) **CLAIM**

The ornamental design for a bus, substantially as shown and described.

DESCRIPTION

FIG. 1 is a front elevation view of a bus in accordance with our design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a front perspective view thereof; and,

FIG. 7 is a rear perspective view thereof.

The broken lines in the drawings illustrate portions of the bus that forms no part of the claimed design.
